Primary Examiner — Kelley Donnelly(74) *Attorney, Agent, or Firm* — Thomas M. Freiburger**CLAIM**

The ornamental design for a locker door, substantially as shown and described.

DESCRIPTION

FIG. 1 is a front perspective view of a first embodiment of a locker door according to my new design;

FIG. 2 is a top plan view thereof, the bottom view being a mirror image;

FIG. 3 is a rear elevational view thereof;

FIG. 4 is a left side view thereof;

FIG. 5 is a right side view thereof;

FIG. 6 is a front perspective view of a second embodiment of a locker door according to my new design;

FIG. 7 is a top plan view thereof;

FIG. 8 is a rear elevation view thereof;

FIG. 9 is a left side view thereof; and,

FIG. 10 is a right side view thereof.
